Primary Examiner — Catherine Tuttle(74) *Attorney, Agent, or Firm* — Blakely, Sokoloff, Taylor & Zafman LLP(57) **CLAIM**

We claim the ornamental design for a dinosaur shaped bubble blower, as shown and described.

DESCRIPTION

FIG. 1 is a perspective view of the dinosaur shaped bubble blower showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are included for the purpose of illustrating portions of the dinosaur shaped bubble blower that form no part of the claimed design.
